United States Patent Office.

THOMAS DONATO, OF NEW YORK, N. Y.

Letters Patent No. 103,854, dated June 7, 1870.

IMPROVEMENT IN WINDOW-BLINDS.

The Schedule referred to in these Letters Patent and making part of the same.

To all whom it may concern:

Be it known that I, THOMAS DONATO, of the city of New York, in the county and State of New York, have invented a new and improved Window-Blind; and I do hereby declare that the following is a full, clear, and exact description thereof, which will enable others skilled in the art to make and use the same, reference being had to the accompanying drawing forming part of this specification.

Figure 1 represents a face view of my improved window-blind.

Figure 2 is a vertical transverse section of the same, taken on the plane of the line $x-x$, fig. 1.

Similar letters of reference indicate corresponding parts.

This invention relates to a new manner of securing pivoted slats in the frames of window-blinds.

The invention has for its object to provide a more secure fastening for the slats, and, at the same time, greater facility for removing the same for repair.

The invention consists in securing each slat A, by means of separate tenons $a a$, to two vertical bars, B and C, the said bars being pivoted, near their upper and lower ends, to small levers D D, that are pivoted, in the centers, to the frame E of the blind. The slats are thus not pivoted directly to the frame, but are

braced and stiffened by the bars B C, which are pivoted to the levers D.

The main advantage of this arrangement is, that that the slats can be readily removed for repair without taking the whole blind-frame apart.

The pivots b of the bars B C can be readily reached, and, as I prefer to make them in the form of screws, they can be removed when desired.

When the bars are removed with the slats, they can be easily taken apart.

Another advantage of this arrangement is, that mosquito-nets may be readily secured to the inner edges of the bars B or C without interfering with the adjustment of the slats.

The bars B C may, however, when desired, be concealed and covered by ornamental moldings, which are fastened to the frame A.

Having thus described my invention,

I claim as new and desire to secure by Letters Patent—

The bars B C and pivoted levers D, combined with the blind-slats A, which have double tenons at both ends, as set forth, all arranged as specified.
